Inventor
George L. Hunt
Williams, Bradbury
See, & McClellan, Inc.

UNITED STATES PATENT OFFICE.

GEORGE L. HUNT, OF BOSCOBEL, WISCONSIN, ASSIGNOR TO THE GEORGE L. HUNT MANUFACTURING COMPANY INC., OF BOSCOBEL, WISCONSIN, A CORPORATION OF WISCONSIN.

GEAR PULLER.

Application filed February 7, 1921. Serial No. 442,925.

To all whom it may concern:

Be it known that I, GEORGE L. HUNT, a citizen of the United States, and resident of Boscobel, in the county of Grant and State 5 of Wisconsin, have invented a certain new and useful Improvement in Gear Pullers, of which the following is a full, clear, concise, and exact description, reference being had to the accompanying drawings, forming a 10 part of this specification:

My invention relates to gear pullers or devices for removing gears, bushings, wheels and the like from associated shafts.

The objects of my invention are:

15 First; to provide a tool of this kind which is quickly adjustable to engage the gear or element to be removed.

Second; to provide mechanism whereby the jaws of the tool are drawn first inwardly 20 to secure a tight grip on the element to be removed, and then longitudinally of the shaft to remove the element, and

Third; to provide a device of this class which may be sturdily and economically 25 manufactured.

My invention will be more clearly understood by referring to the accompanying drawings, in which

Figure 1 is a side view of the device; 30 Figure 2 is a sectional view taken on the line 2—2 of Figure 1, and

Figure 3 is a sectional view taken on the line 3—3 of Figure 1.

In the drawings, 9 indicates a spacer or 35 guide disposed and firmly riveted between the bars 10—10, constituting a frame. Pivoted at 11—11 within the frame formed by the bars 10—10 are a pair of arms 12—12, each of which is provided with a jaw 13 for 40 engagement with the gear or element to be removed. Links 14—14 are pivoted at their outer ends by means of bolts 15—15 to the arms 12—12, and at their inner ends to the nut 25.

45 The guide member 9 is provided with an aperture 16 through which passes freely a screw 17, threaded and operating through the nut 25. It will be seen that by this construction the arms 12 may be rotated about 50 the pivots 11—11 upon longitudinal movement of the screw 17, which slides freely through the opening 16.

In Figure 1 I have shown the gear puller adjusted and in position to remove a gear 55 18 from the shaft 19. In use, by moving the

arms 12 the jaws 13 will be placed around the gear 18, as shown, with the end of the screw 17 in engagement with the end of the shaft 19. Then by operating the screw 17 against the end of the shaft 19, the nut 25 will be moved toward the guide 9, and draw the links 14 in the same direction. The links 14 being pivoted to the arms 12 will also draw the same inwardly to bring the jaws firmly in engagement with the gear 18, and upon further operation of the screw 17 the jaws 13, and thus the gear 18, will travel longitudinally toward the end of the shaft 19. The screw 17 is provided with a squared head to permit its rotation by means of a wrench.

What I claim is:

1. A gear puller comprising a frame, a guide member in said frame, said guide member being provided with an aperture, a pair of arms pivoted to said frame, a threaded nut disposed between said arms and having link connection therewith, and a screw operating through said guide and said nut, said arms arranged to engage a gear to be moved, and said screw arranged to engage the shaft upon which the gear is mounted.

2. A gear puller comprising a frame, a guide member in said frame, a pair of arms pivoted to said frame, a threaded nut disposed between said arms and having link connection therewith, and a screw operating through said guide and said nut, said arms arranged to engage a gear to be moved, and said screw arranged to engage the shaft upon which the gear is mounted.

3. A device of the class described comprising a frame, a pair of arms connected with said frame, a nut, a pair of link members pivoted to said arms and said nut, a screw operable through said nut, said screw arranged on operation to engage the shaft from which a member is to be removed, and to cause the arms to travel first towards the said member, and then in a direction parallel to the axis of the screw.

4. A device of the class described comprising a frame, a pair of arms connected with said frame, a nut, a pair of link members pivoted to said arms and said nut, a screw operable through said nut, said screw arranged on operation to engage the shaft from which a member is to be removed, and to cause the arms to travel in a direction parallel to the axis of the screw.

5. A gear puller comprising a pair of gripping members, a cross-member, each of said gripping members having one end attached to said cross-member, a jack-screw disposed between said gripping members and extending freely through said cross-member at a point intermediate the ends thereof, a nut co-operating with said jack-screw, a pair of links, one associated with 10 each gripping member, each link having one end thereof pivoted to said nut and its other end pivoted to its associated gripping member at a point intermediate the ends of the latter.
- 15 6. A tool of the class described comprising a centrally apertured cross bar, arms piv-

oted to the opposite ends of said bar, jaws on the free ends of said arms, links pivoted at their outer ends to said arms, a head to which the inner ends of said links are pivoted, said head being provided with a central screw threaded aperture, and an ejector screw passing through said aperture in said cross piece and threaded through the aperture in said head. 20 25

In witness whereof, I hereunto subscribe my name this 27th day of January, 1921.

GEORGE L. HUNT.
